ATTORNEY

UNITED STATES PATENT OFFICE.

WALTER S. DOLMAN, OF PHILADELPHIA, PENNSYLVANIA.

MECHANICAL TOY.

1,049,345.

Specification of Letters Patent.

Patented Jan. 7, 1913.

Application filed June 24, 1911. Serial No. 635,070.

To all whom it may concern:

Be it known that I, WALTER S. DOLMAN, a citizen of the United States, residing at Philadelphia, in the county of Philadelphia and State of Pennsylvania, have invented certain new and useful Improvements in Mechanical Toys, of which the following is a specification, reference being had to the accompanying drawing, forming part there-
10 of, in which—

Figure 1 is a side view of the external appearance of a toy embodying my invention. Fig. 2 is a vertical, longitudinal section of the same toy, and Fig. 3 is a horizontal lon-
15 gitudinal section of a different toy also embodying my invention.

My invention is applicable to toy snakes, worms, caterpillars or similar objects which I shall designate as animals of the "snake order" and is intended to simulate their natural movements in locomotion, without legs, wheels or other means of locomotion being visible. This locomotion is accomplished by the animal bending its body, 20 drawing up the tail toward the head and then straightening out, thus pushing the head forward, the tail being held by points or spurs which engage the floor or ground. The body of the animal may be formed of a 25 coil or helix of thin elastic wire, A, covered with oiled silk or other suitable fabric, B, and the head may be stamped out of sheet metal and painted, or it may be covered with the same material as the body.

30 Along the inside of the back, or the convex side or portions of the body, is a flexible back-bone, D, which may be made of thin tempered steel, and a cord, running the length of the body is anchored in the tail at 35 t, and fastened to the mechanism in the head, which mechanism, M, serves to draw it forward and allow it to go back again alternately. When the cord, C, is drawn forward, the head and tail are drawn nearer 40 together, thus bending the body, and when the cord is allowed to go back, the elastic back-bone, D, straightens the body out again, thus pushing the head forward, the tail catching in the floor or ground by

means of the spurs, s, s. Similar spurs may 50 be provided in the head if desired but they are not generally necessary.

The mechanism illustrated embodies ordinary clockwork operated by a coil spring which rotates, by intermediate gearing, two 55 wheels, or disks one on each side. Said disks being provided with eccentric pins, i, i, which engage eyes in the yoke, y. The cord, C, being attached to the eye, d, in said yoke. A fan, f, operated in the usual manner, serves as a brake to prevent the mechanism going too fast. A vibrator and escapement may be used instead of the fan, but I find the clicking of the same objectionable and prefer the fan. 65

The clockwork in the head is of well known construction and forms no part of my invention, and it may be varied within wide limits without departing from the spirit thereof. 70

In Fig. 3, my invention is illustrated as applied to a snake making a double bend of the body or an S shaped bend. The only modification of the mechanism being that the back-bone is in two parts, D' and D'', on 75 opposite sides of the body; the two parts being connected by a rigid connection, E.

What I claim is,

1. In a mechanical toy of the character described, the combination of a flexible 80 back-bone, internally disposed means for alternately bending and releasing said back-bone, and spurs in one end of the toy, permitting progressive movement in only one direction. 85

2. In a mechanical toy of the character named, the combination of a flexible back-bone, a cord extending from end to end of the backbone, means for alternately drawing up and releasing said cord, and means 90 for permitting progressive movement in only one direction.

In testimony whereof I have affixed my signature in presence of two witnesses.

WALTER S. DOLMAN.
